SONIC SYSTEM FOR AUGMENTING THE EXTRACTION OF OIL FROM OIL BEARING STRATA

Albert G. Bodine, Jr., Van Nuys, Calif.

Application February 17, 1948, Serial No. 8,799

7 Claims. (Cl. 166—20)

1

This invention relates generally to systems for increasing the flow of wells, particularly though not necessarily oil wells, and deals more especially with a system for increasing the flow from the oil bearing strata to the well by application to the strata of elastic waves of sonic character, i. e., waves traveling in the strata at the speed of sound. The present application is a continuation-in-part of my prior application entitled Method and Apparatus for Treating Wells, filed May 14, 1941, Serial No. 393,352, now Reissue Patent No. 23,381; and is also a continuation-in-part of my prior application entitled Method and Apparatus for Pumping, Serial No. 761,456, filed July 17, 1947, now Patent No. 2,444,912, which application is a continuation-in-part of my original application of the same title, Serial No. 521,576, filed February 8, 1944. The present application is also a continuation-in-part of my prior application entitled Method and Apparatus for Boundary Layer Control, Serial No. 771,808, filed September 2, 1947, now abandoned.

It is a well known fact that the Nation currently faces a serious petroleum shortage. It is a further known fact that, when an oil well is abandoned for lack of further economical production, more than two-thirds of the oil reserve is still in the ground. In other words, speaking generally, it has, to date, been economically feasible to extract an average of not over about one-third of the potential total recovery from known fields. It need hardly be said that any means for increasing the percentage of recovery would be of extreme value.

It is accordingly the major object of the present invention to provide a system for augmenting the flow from the strata to the well, to the end that a higher percentage of recovery of the total fluid in reserve in the formation may be achieved.

I have found that the rate of migration of oil through wet sandstone can be increased 50% by applying sound waves to the sandstone. By sound or sonic waves, I mean waves of elastic deformation propagated in the formation at the speed of sound, and not necessarily waves limited to the frequency range of human hearing ability. In the transmission of sound waves through an elastic medium, such as a stratum of sandstone, the movement of the individual particles of the medium is purely local, each particle making small to and fro excursions in a manner similar to the vibrating body generating the waves. The particles move largely in the same line as the directions of propagation of the wave, but with only a very small amplitude of travel or displacement.

My invention contemplates the utilization of such movement of the particles in response to sound waves for the accomplishment of a flow of fluid through the porous oil bearing earthen formation adjacent to an oil well. This I usually accomplish by establishing within the medium

2

transmitting the sound waves a resonant condition in which a large part of the energy supplied by the generating vibrator is stored in the medium by the reflection of the sound waves in such a manner as to reinforce these originating with the generating vibrator to establish within the medium a standing wave. This reinforcement by reflection continues and increases the amplitude of the standing wave.

10 The invention is made more effective by the fact that sound waves properly applied directly to an oil bearing stratum will be confined thereto, and not dissipated in adjacent non-bearing earthen strata, because of the substantial difference in acoustic impedance as compared with adjacent strata. Thus, waves are found to be reflected at the boundaries of the oil-bearing stratum and so confined against dissipation outside. The energy transmitted to the oil bearing stratum is accordingly kept within the stratum, resonance may be established therein, as mentioned in the preceding paragraph, and the oil bearing structure thus made to absorb a very substantial quantity of wave energy.

15 20 25 It is beyond the scope of this disclosure to theorize all of the reasons why the invention is effective. However, the following factors are apparent:

Sound waves traveling in an elastic medium are 30 subject to attenuation, the lost energy of the wave being converted into heat. Heat generates gas pressure, as well as reducing the viscosity of the oil, and hence oil migration must be increased.

Oil is trapped in earthen formations by water 35 "filaments" bridging the gaps between sand particles. Periodic acceleration of the formation by transmitting sound waves therethrough causes or permits the oil droplets to puncture these water filaments, and so to become freed for migration.

40 Oil exhibits boundary layer adhesion to the surfaces of the sandstone, which seriously impedes the flow of the oil to the well, but which can be materially reduced by transmitting sound waves through the sandstone, the oil or both. Such waves act to reduce the frictional drag of the formation on the well fluid by agitating, breaking up and scrubbing away the boundary layers of the fluid which are otherwise bound adhesively to the formation.

45 50 55 Whether or not the above factors are exhaustive of the flow promoting conditions established by the invention, is a question beyond present knowledge. Suffice it to say at this time that I have found sound waves applied to an oil bearing earthen formation to materially augment the flow rate therethrough.

The broad invention consists of a system of direct application of sound waves to an oil bearing stratum to augment the flow rate through the formation to the well, and the percentage of ultimate recovery of the total reserve present in the stratum.

The invention further includes methods and apparatus of various classes for applying the sound waves to the producing structure. The invention is applicable both to pumping wells and flowing wells. It is also within the capabilities of the invention to transmit sound waves from the region immediately adjacent one well to regions adjacent other wells, and thus to augment the flow rate from a group of wells in the formation, though using but a single well as a source of waves. Further, I may employ an abandoned well as a powerful source of sound waves by installing high power sound wave generating apparatus therein, with no revived production from that particular well attempted. The high energy waves transmitted into the formation from the high power apparatus thus installed are propagated for a considerable distance through the stratum, and may thus revive wells over a substantial field area.

Since well casings are perforated in the region of producing structure, it is very often sufficient to apply the waves to the fluid inside the well. This sonic wave energy is radiated through the perforations directly into the producing formation. In some instances I prefer to increase the area of the perforations to increase wave transmission efficiency.

Various additional objects and features of the invention in its several illustrative forms will be made apparent in the course of the following detailed description of several present embodiments thereof selected for illustrative purposes. For this purpose, reference is directed to the accompanying drawings, in which:

Figure 1 is a longitudinal sectional view, partly in elevation, showing one embodiment of the invention;

Figure 2 is a somewhat diagrammatic view showing a simplified form of the invention and showing also a standing wave pattern;

Figure 3 is a longitudinal sectional view, partly in elevation, showing another modification of the invention;

Figure 4 is another view partly in longitudinal section and partly in elevation showing another embodiment of the invention; and

Figure 5 is a view, partly in longitudinal section and partly in elevation, showing another embodiment of the invention.

The process of the present invention, in one general aspect, involves and depends upon several important steps, viz: generating high energy sound waves, efficiently transmitting said waves to the productive formation, and effecting an efficient energy transfer between the transmission means and the formation. Several distinct forms of apparatus in accordance with the invention for accomplishing this process are disclosed herein, and the process invention may most conveniently be understood from a consideration of these several forms of apparatus as employed in different illustrative applications of the invention.

Referring first to the application of my invention illustrated in Figures 1 and 2 wherein sound wave generating apparatus is installed in an abandoned oil well (or earth bore not to be used as a producing well) numeral 10 designates well casing sunk in bore 11 to the region of oil productive stratum 12. Such casings may originally have extended to the bottom of the bore, but for present purposes is preferably cut off near the top of the oil-bearing stratum 12, as indicated.

An elastic compression column 14, composed of

a good grade of elastic steel, is suspended within casing 10, and has mounted on its upper end sound wave generator 15, one embodiment of which is to be described in more particular hereinafter. This elastic column 14 is of sufficient diameter for its length to transmit longitudinal elastic waves of compression, and by use of the expression "compression column" I have reference to this "stiffness" characteristic. Near the upper end of column 14, the column is furnished with an enlarged head or collar 16. The column 14 fits in an aperture 17 formed in a horizontal top plate 18, the head 16 overhanging and bearing downwardly on said plate around aperture 17 for the support of the column. Vertically spaced below top plate 18 is a horizontal bottom or base plate 20 carried by tubular member 21 and flange 22 bolted to casing head flange 23. Between base plate 20 and top plate 18 are a plurality of coil springs 24, positioned on vertical pins 25 set tightly into base plate 20 and projecting with working clearance through bores 26 in top plate 18. The weight of the column 14 is thus transferred to springs 25, and thence to the casing 10 supported by the earth.

A body of cement 27 is filled in the well bore around the lower portion of the column. If desired, the column may be grooved as at 28 to key the column to the cement body and thus assure 30 vibrating movement of the latter with the column. Alternatively, a body of packed wet sand may be used in place of the cement. This body of cement or sand, as the case may be, places the elastic column in solid-to-solid engagement with the 35 formation, thus providing good wave energy transmission between the column and the surrounding formation, as more fully described hereinafter.

Sound wave generator 15 comprises a housing 40 30 containing a means for setting up vertically directed vibrations and thereby exerting a vertical oscillating force upon the upper end of the column 14. The means for generating these vibrations may be mechanical, electrical, hydraulic 45 or any other type capable of delivering sufficient power. A type of generator well adapted for the purpose has meshing oppositely rotating gears 31 carrying eccentric weights 32 which balance out horizontal vibrations but cause vertical vibrations to be additive to produce a substantial resonant oscillatory force in a vertical direction. The driving pulley 33 of the sound wave generator, mounted on the shaft for one of the spur gears, is driven by an electric motor 50 55 or any other suitable prime mover (not shown) through belt 36.

In a simplified embodiment of the invention, the column 14 may consist of a steel column of substantially uniform diameter from the generator 15 to its lower end. Such an embodiment is somewhat diagrammatically represented in Figure 2, together with a typical standing wave pattern therefor. For simplicity, the operation of the apparatus of Figure 1 will first be described with the assumption that the column 14 is actually of uniform diameter from top to bottom.

Generator 15 applies an oscillating force in a vertical direction to the upper end of elastic column 14, thereby launching alternating elastic deformation waves of tension and compression in a longitudinal direction down the column, said waves traveling in the elastic column with the speed of sound. The transmission of elastic waves along the length of an elastic column is

a well understood phenomenon usually treated of in works on acoustics under the heading of "longitudinal vibrations of rods" and need not be explained in great detail herein. It should, however, be understood that longitudinal elastic waves in an elastic column cause sections of the rod to oscillate longitudinally of the column, with a displacement amplitude depending upon the energy of the wave and the longitudinal stiffness of the column.

The column 14 is usually long relative to a wave length measured along the column. Waves in the approximate frequency range of 10 to 30 cycles per second appear to give the desired high amplitude waves capable of traveling long distances in the formation, e. g., hundreds of feet. A 20 cycle wave has a wave length in the column of the order of 800 feet, and the column may hence be several wave lengths (fundamental frequency) long for a typical oil well installation. Various harmonics, of lesser wave lengths, may also appear.

It will of course be clear that the wave frequency is determined by the speed of the sound wave generator 15, and that by varying the speed of the latter, all or any of the desired ranges of frequencies may be employed. The vibration amplitude of the generator will of course depend upon its frequency, and it is found that a moderately low sonic frequency, as 10 to 30 cycles, affords the necessary vibration amplitude for equipment of the type herein disclosed.

For efficient transmission of the wave energy from the generator down the elastic column, the generator should be adjusted to a resonant frequency of the column, so as to establish a standing wave along the column, as represented in Figure 2, this being accomplished in the case of a column with "free" ends, by adjusting the speed of the generator to produce such a wave length along the column that the column length is equal to an even number of quarter wave lengths. The standing wave results from interference of waves reflected by the ends of the column with the generated wave, as is well understood in the art of acoustics. In an actual installation the lower end is not entirely "free" because it is reactively connected to the formation so that the latter becomes part of the resonant circuit. Nevertheless, good reflections of waves occur at the lower end. The conventional standing wave diagram to the right of the column in Figure 2 represents the envelope of vibration amplitude at various sections along the column, assuming moderate reactance at the lower end, and it will be observed that the upper and lower end sections of the column, as well as sections spaced by a half-wave from the column ends, experience substantially maximum vibration amplitude, while sections midway therebetween experience zero or minimum amplitude. The terms "velocity anti-node" and "velocity node" are conventionally applied to the maximum and zero amplitude regions of the standing wave, as indicated at V and V', respectively, in Figure 2. Such resonant standing wave conditions assure optimum power transmission from the generator down the column to the body of cement 27, and thence to the formation.

The use of a vibration generator 15 characterized by simple harmonic motion is of substantial importance, since such a generator generates sound waves permitting the application of acoustic methods to accomplish good energy transfer between the steel column and the for-

mation. Good coupling and good energy transfer to the earthen foundation is desired especially in the more powerful forms of my invention, such as those employing steel columns, because large amounts of energy can be transmitted without over-stressing the steel if the energy is rapidly transmitted from the bottom to prevent excessive resonant amplitude. Such energy transfer depends upon the provision of a good impedance match between the column and the formation, which is accomplished by the use of a column having heavy mass and large area in contact with the formation, or with the cement body, which is in turn a heavy body of large surface in contact with the formation. In the case of a filled-in body of packed sand, such body is very tightly packed under the high pressure involved, and becomes, in effect, a part of the formation. A determination of the weight of the bottom end portion of the column in engagement with the formation is also governed by the frictional resistance to its reciprocation and by the resistance to its movement offered by the material in contact therewith, or with the cement body in which it is embedded. The bottom end column portion (section 42 of Figure 1) must be made of sufficient weight that its efficiency as an energy transmitting member is not overcome by the inertia and other resistance to motion of its environment, which, if the column is very light, may serve to damp out entirely its movement and render negligible the wave energy transmitted thereby.

In operation, elastic waves generated at the top of the column are transmitted down the column as periodic alternating waves of tension and compression, the waves preferably being generated at a resonant frequency of the column, all as already explained. These waves set the lower end portion of the column into vertical oscillation, from which the wave energy is transmitted to the cement body 27, and thence to the surrounding earth formation in which the cement body is embedded. The wave energy so delivered to the elastic earth formation travels radially outward in the latter with the speed of sound. These elastic waves traveling in the oil bearing stratum 12 are reflected at the boundaries thereof by reason of the substantial difference in impedance usually encountered in two adjacent strata. With high energy waves of steep wave front such as may be transferred to the earth formation with the apparatus of Figure 1, the wave action is effective for hundreds of feet to augment the flow rate through the earthen formation by reason of heating, removal or reduction of the adhesive boundary layer on the surfaces within the interstices of the formation, and removal or puncture of internal flow-impeding water filaments in the formation.

The specific elastic column 14 of Figure 1 is made up of several sections 40, 41 and 42 of increasing cross-sectional area and massiveness in a downward direction, the bottom section 42 being for example 7½" in diameter, and about 110' long. The increasing cross-section causes an increase in longitudinal dynamic stiffness, which results in turn in reduced amplitude of vertical oscillation. The reduction in amplitude of oscillation, however, is accompanied by a corresponding increase in the force with which the column moves. The "tapered" column thus functions as an acoustic lever, transforming the wave energy delivered by the generator to a higher impedance state characterized by reduced-

amplitude of travel and correspondingly increased force. This higher impedance wave energy in the massive lower end section 42 of the column is appropriate for the high impedance load (the earthen formation) which the elastic column must drive. It should also be noted that the increased mass and surface of the lower section 42 of the column is also of advantage from another standpoint, in that the coupling between the column and the formation is thereby improved. Increased energy transfer from the column to the formation is thus accomplished.

If there be employed as a prime mover for driving the generator 15 a gas engine, or a non-synchronous electric motor, it will be found that the engine or motor will automatically assume a speed establishing one of the modes of resonant operation of the wave train in the column. Approaching resonance, any increase in speed of the prime mover automatically considerably increases the amplitude of oscillation, thus increasing the energy load on the prime mover, so that the prime mover "runs up against the load," or in other words, holds that speed corresponding to the maximum torque it is adjusted to develop. If for any reason the prime mover should tend to slow down, the wave amplitude would appreciably decrease, thereby considerably reducing the load, whereby the prime mover would at once regain its lost speed. Increase in speed without increasing the energy input into the prime mover is prevented by the substantial increase in load that automatically follows any increase in speed. The system operated in this manner is thus automatically governing.

In other embodiments of my broad invention, I may locate the wave generator at the ground surface, and utilize the well fluid column as a wave transmission path to the oil bearing formation. This practice is particularly feasible with flowing wells, and Figure 3 shows a well equipped with this variation of my invention. Numeral 80 designates the well bore, 81 the casing, perforated as at 82 opposite the oil bearing formation 83, and 84 the flow tubing suspended inside casing 81. The upper end of tubing 84 is screwed into casing head 85, the flow being received above head 85 by nipple 86 screwed into the stem of T 87. To one arm of T 87 is screwed pipe line 88 containing valve 89, and to the other arm is coupled cylinder 90 containing piston 91 reciprocated by eccentric 94 and connecting rod 93, the eccentric being driven by rotating shaft 96 powered by any suitable prime mover, not shown.

Figure 3 also shows a pipe 97 coupled at one end to casing head 85, so as to communicate with the annular well fluid space 98 between the casing and the tubing 84. The other end of this pipe 97 is coupled to cylinder 100 containing piston 101 reciprocated by eccentric 102 and connecting rod 103, the eccentric being driven by shaft 104, powered by any suitable prime mover, not shown.

The apparatus shown in Figure 3 has several alternative methods of operation. Assume first that the piston 91 is inactive, but the piston 101 to be reciprocated at sound wave frequency. The piston 101 is in communication with the well fluid which has arisen in the casing around the tubing 84 and has entered pipe 97 and cylinder 100, and consequently generates sonic pulses in the fluid which travel down the fluid column in the casing with the speed of sound. Reaching the lower end of the casing, these

sound waves are transmitted radially outward through the casing perforations and into the surrounding oil bearing formation, where they perform their function of augmenting the flow rate to the well.

Alternatively, the piston 91 may be reciprocated at sonic frequency to generate sound waves in the production fluid column in the tubing 84. The sound wave pulses so transmitted to and beyond the open unimpeded lower end of the tubing 84 fan out therefrom into the formation at the bottom of the well to create elastic wave motion in the formation for the purpose and with the effects previously described.

The apparatus of Figure 3 is also illustrative of the system for injecting water or other fluid into a well to wash oil in the formation toward adjacent wells. It is only necessary to assume that instead of utilizing pipe 88 as the delivery line of the flowing well, the wash water or other fluid is being pumped into pipe 88 to be forced down tubing 84 and finally into the formation. The reciprocating piston 91 may then impress the sonic impulses upon this descending column of wash fluid, with the result that the impulses are radiated into the formation and increase the fluid flow rate therethrough. It is of course also within the scope of the invention to transmit sonic waves into the formation by utilizing the piston 101 and fluid column between casing 81 and tubing 84 in connection with the pumping of wash fluid down the tubing 84.

Forms of my invention wherein the sound wave energy is transmitted by a fluid column, for instance those represented by Figure 3, are greatly aided in their ability to transmit power by maintaining a high mean pressure on the fluid, "mean pressure" being the static pressure level above and below which the fluid pressure alternately rises and falls with passage of the sound wave. It is thus desirable, for the transmission of large amounts of power, that the mean pressure be as high above atmospheric as practicable. Because of the hydrostatic head of the column, the mean pressure in the lower regions of the well will be exceedingly high. A mean pressure above atmospheric can be imposed on the fluid column in the well in the case of a flowing well by closing down somewhat on the valve 89, thus imposing a back pressure on the fluid column. Closing this valve of course tends to reduce the flow rate, but in some cases the overall effect will be to increase the flow rate by transmitting stronger sound waves into the formation. The pressure on the fluid column in the case of pumping wash fluid down the tubing 84 is of course under the control of the pump supplying the wash fluid, and can be increased by increasing the delivery pressure of the pump. Additional power transmission down a fluid column is also gained by resonating the column. For instance, the piston 91 can be operated at a resonant frequency of the pipe 84, creating a standing wave in the fluid column, as well understood in the science of acoustics. A similar result can be obtained by operation of the piston 101 at a resonant frequency of the fluid column between the casing 81 and tubing 84.

In Figure 4 is illustrated an embodiment of my invention in which sound wave impulses are transmitted to the oil bearing formation through a well casing 110, the pumping equipment having been removed. The figure in this case, for simplicity, omits a showing of the well bore and casing above the lower region of the well, since

these parts are conventional, but the vibration generator at the ground surface is shown, together with an upper end portion of the elastic vibration transmitting column. In this embodiment there is secured to the lower end of an elastic column 111, which preferably may be a string of elastic sucker rod sections 111a, 111b, and 111c of progressively increasing cross-section in a downward direction, a massive body 112. Milled into the sides and bottom of this body are slots 113 in which are received anchor shoes 114 pivotally mounted on pins 115 set into the body 112. The shoes 114, shown in expanded position in the full lines of the drawing, are provided with casing engaging serrations 117 adapted to engage and grip the casing, the shoes being moved to expanded position by coil springs 118 placed between the shoes and the body, as indicated. In the expanded, casing gripping position, the anchor shoes extend angularly downward and outward from their pivot mountings on the body so that the weight of the body 112 and column 111, or a portion thereof, if imposed on the expanded shoes in engagement with the casing, will cause the serrations to bite into the casing.

The shoes 114 may be retained in retracted position during installation in any suitable manner. For instance, they may be initially secured down against expansive springs 118 by a shear wire 119 adapted to be sheared by a small weight 120 movable in a central body cavity 121 through which the wire 119 is caused to pass by way of apertures 122. Transmission of vibratory energy down the column 111 in the manner presently to be described will vibrate the weight 120 against the wire 119 and cause it to fatigue and break, whereupon the anchor shoes are expanded by the springs and grip the casing.

The weight of the body 112 together with a portion of the weight of the column 110 is permitted to be assumed by the casing, causing an elastic deformation of the casing in a downward direction. Of course the casing will part if too heavily loaded, so care must be exercised that only enough loading be transferred to the casing to give it the desired elastic deformation.

A sonic frequency vibration generator 125 at the ground surface is operatively connected to the upper end of the elastic column 111. This generator 125 in this instance comprises an electric motor 126 whose shaft 127 operates an eccentric 128 in the strap 129 of a connecting rod 130. The rod 130 is pivotally connected at 131 to an intermediate point 132 of a lever 133, one end of which has a pivotal mounting 134 on frame bracket 135 of motor 126, and the other end of which is pivotally connected to the upper end of column 111. It will be seen that rotation of motor 126 will result in connecting rod 130 being driven to oscillate lever 133, and thereby reciprocate the upper end of column 111 through a short vertical displacement distance. This movement of the upper end of column launches alternating elastic waves of compression and tension down the column, causing the lower end portion thereof, and the body 112, to oscillate vertically at the frequency of the generator 125. This oscillation is transmitted via shoes 114 to the casing, causing the whole lower end region of the latter to participate in the oscillation. The casing acts as a spring supporting part of the load of body 112, thus oscillating locally in unison therewith. It must be understood that in all ordinary situations the column 111 will not

be bodily reciprocated, the wave lengths of the waves transmitted in the column being much shorter than the column length. In accordance with well known principles of vibrations in rods, different portions of the column may be moving in opposite directions owing to the progress of the wave action down the column.

Preferably, to assure maximum power transmission down the column, the wave generator 125 is operated at a resonant frequency of the column, so as to establish a standing wave therewith, which may be generally similar to that diagrammed in Figure 2, having a velocity anti-node at the top, a velocity anti-node at the bottom (where the engagement is made with the casing), and a number of half-wave spaced velocity anti-nodes between. The mass of the body 112 at the lower end of the column 111 will have a reduced amplitude of oscillation because of the increased longitudinal dynamic stiffness of the column sections 111b and 111c, and also because of its own ample acoustic impedance, but this reduction is accompanied by a desirable increase in force such as is necessary to oscillate the casing and to transmit substantial wave energy to the formation outside.

As already partially described, the suspension of the column from the lever 133 is so adjusted that a portion of the column weight along with the weight of the body 112 will be transferred to the casing, thus imposing a net "bias" on the casing causing an elastic deformation thereof. If the wave amplitude of cyclic displacement of the body 112 as driven by the column 111 is less than the supporting bias deformation of the casing the latter will oscillate in step with the body 112. The elastic wave energy is transmitted from the casing to and into the formation by direct contact therewith.

Figure 5 shows an embodiment of my invention similar to subject matter first disclosed in my aforesaid application Serial No. 761,456. In said figure, numeral 136 designates the perforated casing in the well bore, and 137 an elastic steel pump tubing suspended therein from coil type springs 138, the upper end of said tubing delivering well fluid to pipe 139. A sonic wave vibration generator 140, like the generator of Figure 1, is mounted on the top end of the tubing.

A check valve seat ring 141 is tightly mounted in the tubing, near the lower end thereof, and is provided with check valve ball 142, while the lower end of the tubing is flared out laterally, nearly to the diameter of the casing, as indicated at 144.

In operation, generator 140 transmits elastic waves of tension and compression down the pump tubing, causing the lower end portion thereof (including not only the flare 144 but the ring 141) to be longitudinally reciprocated through a short displacement distance at the frequency of operation of the generator 140, this action, and the preferred establishment of resonance in the tubing, are fully discussed in my application Serial No. 761,457. Each down stroke of seat ring 141 with the tubing occurs at an acceleration greater than gravity, and the check valve ball accordingly unseats during such time. Fluid displaced by the downwardly traveling seat ring therefore flows up through said ring and fills the void above the ring caused by the down stroke of the latter. On the upstroke of the ring, the check valve ball seats, and the column of fluid thereabove is elevated.

The flared lower end of the vertically oscillat-

ing pump tubing, working with relatively close fit within the casing, functions as a piston in the casing to reciprocate a substantial column of well fluid, and hence furnishes a good wave transmission coupling to the fluid. Sound waves are accordingly set up in the fluid, and are radiated to and through the casing and into the surrounding oil bearing formation.

It should be noted that many or all of the embodiments of pump disclosed in my application Serial No. 761,457 will afford some coupling with the well fluid, but that in all cases excepting Figures 5 and 6 of said prior application, the degree of coupling is entirely negligible, and sound waves would not in practice be radiated as far as the oil bearing formation outside the casing. For example, the end area of the pump tubing in the embodiment of Figure 4, or the end area of any of the pistons used with the embodiment of Figure 20, would be an insufficient fraction of the cross-sectional area of the casing for any effective wave transmission coupling to the external well fluid to be expected. The insignificant amount of fluid moved by these areas on each down stroke thereof simply escapes by moving radially out of the way and then up in the large annular space between the pump tubing and the casing, with exceedingly poor coupling efficiency. By having the pumping member nearly fill the casing, however, as does the flared type of tubing end, a substantial quantity of fluid is positively driven, as by a piston in a cylinder, and sufficient wave energy is transferred to the well fluid to be radiated out into the formation.

The various embodiments of my invention all operate by establishment in the oil bearing stratum of strong waves of elastic deformation. As already pointed out, these waves may operate in various ways to increase the flow rate in the formation, including heating, destruction of boundary layer adhesions, and puncture of water films or filaments. The heating effect is useful not only in the earthen formation, but, in some forms of my invention, within the well itself. For instance, in the flowing well installation of Figure 3, the heating effect occurs throughout the entire oil column as well as in the formation, and hence serves to reduce the viscosity of the oil in the column, with inevitable increase in production rate.

It must be understood that the method and apparatus of the present invention are characterized by continuous operation over long periods of time, with large energy transfer to the formation. While all the factors involved are not yet known, it appears necessary that operation be sustained over time intervals of the order of days to secure the desired results.

Reference is here made to my continuation-in-part application entitled Method and Apparatus for Augmenting the Flow of Oil From Pumped Wells, Serial No. 50,428, filed July 23, 1948, in which is disclosed and specifically claimed the subject matter of Figure 5 hereof.

Various illustrative embodiments of my invention have now been described. It is of course to be understood that these are not to be regarded as the only forms which the invention can take in practice, and that the invention is to be limited only in accordance with the language of the following claims.

I claim:

1. For use in a system for reducing the clog-

ging of oil flow passages in a production well or in the oil bearing formation therearound in a production oil field, which system has an elastic sound wave generator at the ground surface adapted to set up elastic waves in a wave transmission medium in a well hole in said field, the improvement comprising a wave transmission medium in the form of a stiff elastic compression column extending down the well hole, acoustically coupled to the wave generator at the ground surface, and acoustically coupled to the oil bearing formation at the bottom, said compression column transmitting alternating elastic waves of compression and tension from said generator into said oil bearing formation to be expended therein.

2. The subject matter of claim 1, wherein the acoustic coupling between the column and the formation comprises a packing of granular particles between the lower end portion of the column and the formation.

3. The subject matter of claim 1, wherein said column has near its lower end a surface set or packed in a solid material in engagement with an uncased area of the oil bearing formation.

4. The subject matter of claim 1, wherein said compression column comprises a plurality of rod sections of progressively increasing cross-sectional area in a downward direction.

5. In an apparatus for use in reducing the clogging of oil flow passages in a production well or in the oil bearing formation therearound in a production oil field, the combination of a solid elastic compression column, capable of transmitting elastic waves of both tension and compression, positioned in the well hole, a vibration generator mounted on the top of said compression column, spring support means for vertically supporting the upper end portion of said column and the vibration generator, and means for acoustically coupling the lower end portion of said compression column to the oil bearing formation.

6. The subject matter of claim 5, wherein said compression column comprises a plurality of rod sections of progressively increasing cross-sectional area in a downward direction.

7. The subject matter of claim 1, wherein a plurality of said elastic wave generators operable at different wave frequencies comprise the column vibrating means.

ALBERT G. BODINE, Jr.
